CONTAINER

Fred A. Sawyer, South Bend, Ind., assignor to
 United States Rubber Company, New York,
 N. Y., a corporation of New Jersey

Application December 30, 1942, Serial No. 470,700

5 Claims. (Cl. 150—0.5)

This invention relates to containers for storing liquids, and especially to containers for storing gasoline for aviation motors, distilled water for storage battery installations and the like.

It is usual at places where large quantities of motor fuel must be kept, to store gasoline in large metal tanks, holding thousands of gallons, and disposed either above or below the surface of the earth. Such metal tanks and the piping necessary to their use require time, heavy equipment and large numbers of skilled workmen for their installation, and once installed, they are more or less permanent, that is they cannot readily be moved. In military operations it is important to be able readily to transport and set up containers for the storage of large quantities of aviation fuel or other liquids.

The present invention provides means for accomplishing this objective by providing a novel form of light, flexible, collapsible storage containers which are capable of holding large quantities of liquid and which can be readily transported and set up. In carrying out my invention, I provide a flexible liquid container formed of a relatively small quantity of impervious material, and I provide a separate supporting means for the container which surrounds the container and supports the hydrostatic forces of the confined liquid, relieving the impervious container of all stresses due to the weight of the stored liquid. In this manner a light and easily transported container is provided having a minimum quantity of impervious material, the outer support being made of readily available and inexpensive materials which need not be impervious to the stored liquid.

In the accompanying drawing:

Fig. 1 is a perspective view of one form of container embodying the invention; and

Fig. 2 is a vertical section through the container shown in Fig. 1, on a plane indicated by the line 2—2 of Fig. 1.

The storage container includes a closed cylindrical container 10 formed of any suitable light weight, flexible material which is substantially inelastic and is inert and impervious to the liquid to be stored. Preferably the material is inert to aromatic hydrocarbon fuels. An example of such material is textile fabric impregnated and coated with a suitable synthetic rubber or rubber-like composition such as the olefin polysulfide plastic material known in the trade as Thiokol. The container 10 is cylindrical in form and has a top wall 12 and a bottom wall 14 connected by a cylindrical side wall 16. Preferably fabric im-

regnated with the inert material is cut in pieces of the proper size and shape and the pieces are cemented or vulcanized together, with or without sewing, all joints being rendered impervious to the liquid in any suitable manner known in the art.

A ground cloth 18, for example of heavy canvas, preferably circular in form and of considerably greater diameter than the diameter of the container, is secured to the bottom wall, either by adhesive cement or by tabs 20 bonded to the bottom wall and fastened to the ground cloth in any suitable manner, as by rivets.

The container is surrounded and supported by an outer wall 22 formed of any suitable flexible and substantially inelastic material, such as canvas of suitable tensile strength. This outer wall forms a cylinder whose diameter is less than the diameter of the container 10 when unconfined, so that when the container is placed in the outer wall the container must necessarily pucker slightly as indicated in Fig. 2. Thus when the container is filled with liquid its walls are slack, and all of the horizontal hydrostatic forces due to the liquid are supported by the outer wall, there being no stress on the container itself due to the presence of liquid. Accordingly, the inner container may be made of very light weight material and requires only a minimum quantity of impervious material for its construction.

The wall 22 is supported in upright position by substantially rigid stakes or posts 24 which are firmly supported in a vertical position. Preferably the stakes are driven into the ground through appropriate openings 26 in the ground cloth, disposed substantially on the circle formed by the horizontal projection of the wall 22. The stakes are preferably contained in sleeves 28 sewed to the side wall 22 opposite the openings 26. The sleeves may be secured to the stakes by wing nut bolts 27.

When the device is assembled the ground cloth is first drawn taut to insure that the bottom wall of the container is flat. The stakes are then inserted in the sleeves and are driven into the ground through the holes 26. The holes serve to locate the stakes accurately and the stakes hold the ground cloth taut to insure that the bottom wall of the container is flat while the device is being assembled, subject only to the slight puckering referred to. This locates the circular corner between the bottom wall 14 and side wall 16 accurately against the outer wall 22, so that this corner is firmly supported by the outer wall when the container is filled. The top and bottom edges

of the wall 22 are preferably secured to the stakes by rivets, bolts, hooks or any suitable means, to insure maintaining the wall both upright and in contact with the ground, thus assuring that the wall will extend throughout the height of the container and support all parts of its vertical wall.

The stakes are provided with suitable top pieces 30 which protect the tops of the stakes while they are being driven, and which support hooks 32 for supporting a rope 34 by which the side wall of the container is supported in upright position through tabs 36 secured to the container and through which the rope is passed.

The container may be filled, drained, and vented by any suitable conduits preferably all attached to a single plate or support 38 secured in any suitable manner to an opening in the top wall. As illustrated a vent pipe 40 and a filling and emptying pipe 42 are secured to the plate 38. The pipe 42 is preferably flexible, for example being formed of a Thiokol hose, so that the container can be collapsed and rolled up without danger of injury. The weight of the plate and pipe connections may be supported by a rope 44 suspended from a pole 46 secured to the tops of appropriate stakes.

Having thus described my invention, what I claim and desire to protect by Letters Patent is:

1. A liquid storage device comprising in combination a closed container formed of flexible substantially inelastic impervious material and including a circular bottom wall and a circular top wall connected by a cylindrical side wall, an outer wall of flexible substantially inelastic material surrounding the container, the diameter of the outer wall being less than the normal diameter of the container when unconfined, a plurality of supporting members rigidly supported in upright position and disposed adjacent the outer wall, the outer wall being secured to the supporting members, and means secured to the bottom wall of the container and to said supporting members to maintain said bottom wall flat between the supporting members.

2. A liquid storage device comprising in combination a closed container formed of flexible substantially inelastic impervious material and including a circular bottom wall and a circular top wall connected by a cylindrical side wall, an outer wall of flexible substantially inelastic material surrounding the container, the diameter of the outer wall being less than the normal diameter of the container when unconfined, a sheet of flexible material secured to the bottom wall of the container and extending substantially beyond

the outer wall, said sheet having a plurality of openings therethrough disposed substantially on the circle formed by the horizontal projection of the outer wall and a plurality of upright substantially rigid supports attached to the outer wall and extending through said openings.

3. A liquid storage device comprising in combination a closed container formed of flexible substantially inelastic impervious material and including a circular bottom wall and a circular top wall connected by a cylindrical side wall, an outer wall of flexible substantially inelastic material surrounding the container, the diameter of the outer wall being less than the normal diameter of the container when unconfined, a sheet of flexible material secured to the bottom wall of the container and extending substantially beyond the outer wall, said sheet having a plurality of openings therethrough disposed substantially on the circle formed by the horizontal projection of the outer wall, a plurality of upright sleeves secured to the wall and disposed in alignment with the openings in said sheet and a plurality of substantially rigid supports disposed in said sleeves and passing through said openings, said supports being secured to said outer wall.

4. A liquid storage device comprising in combination a closed container formed of flexible substantially inelastic impervious material and including a circular bottom wall and a circular top wall connected by a cylindrical side wall, a cylindrical outer wall surrounding the side wall of the container and extending throughout the height of the container, said outer wall being formed of substantially inelastic material and having a diameter less than the normal diameter of the container when unconfined, and means secured to the bottom wall of the container and extending beneath and outside of the outer wall for holding the bottom wall flat.

5. A liquid storage device comprising in combination a closed container formed of flexible substantially inelastic impervious material and including a bottom wall and a side wall, an outer wall of flexible substantially inelastic material surrounding the container, a plurality of spaced supporting members disposed in an upright position adjacent the outer wall and connected thereto and a ground cloth secured to the bottom wall of the container and extending outwardly of the outer wall and cooperating with the said supporting members for maintaining said bottom wall in a substantially flat condition between the supports.

FRED A. SAWYER.
